UNITED STATES PATENT OFFICE.

GEORGE L. MARTIN, OF BINGHAMTON, NEW YORK, ASSIGNOR TO BUNDY MANUFACTURING COMPANY, A CORPORATION OF NEW YORK.

PRINTING-MACHINE.

1,005,565.

Specification of Letters Patent. Patented Oct. 10, 1911.

Application filed February 2, 1905. Serial No. 243,855.

To all whom it may concern:

Be it known that I, GEORGE L. MARTIN, a citizen of the United States, and a resident of Binghamton, county of Broome, State of New York, have invented new and useful Improvements in Printing-Machines, of which the following is a specification.

My invention relates to printing machines and to machines for bringing suitable characters upon a printing or reading line.

It has for its object to improve and simplify the mechanism of such machines; to render the parts easier of action and adjustment; to improve the hammer operating mechanism; to provide means for varying the pressure of the printing blow under varying circumstances; to provide an improved movable printing carriage and means for protecting certain of the printing parts and their connections, especially certain parts of the mechanism for operating the hammers; also improved means for operating a name wheel and for making it stand during the operation of the machine at the ditto point unless positively moved otherwise; also means for varying the pressure of the printing blow in connection with the action of the ditto marks; also to provide a counter for keeping a record of the number of operations of the machine; also for improving and simplifying the keyboard and its connections and the means for enabling the keys to set the type segments in printing or reading position.

In the drawings accompanying this specification and forming part hereof I have shown one form or embodiment of my invention which I will now proceed to describe. My invention as there shown is embodied in a machine provided with a bank of keys of the usual character and arranged to bring upon a printing line numbers corresponding to the value of the keys depressed and to print the said numbers upon a suitable record strip, and also to add such numbers upon a set of adding wheels, and, when desired, to print the total represented by such adding wheels.

Referring now to the drawings of such form of machine, Figure 1 is a side view of such machine; Fig. 2 a plan; Fig. 3 a plan of the interior with the top plate and the keyboard sections removed; Fig. 4 a vertical longitudinal section on the lines

4—4 of Fig. 3; Fig. 5 a similar section on the lines 5—5 of Fig. 3; Fig. 6 is a central longitudinal section on the lines 6—6 of Fig. 3; Fig. 7 a longitudinal section on the lines 7—7 of Fig. 3; Fig. 8 is a side elevation of the mechanism looking in the same direction as in Fig. 7 taken on lines 8—8 of Fig. 3; Fig. 9 is a rear view of a portion of the inside of the machine showing a rear view of the carriage; Fig. 10 is a detail connected with the hammer trip mechanism of the name wheel; Fig. 11 is a cross-section of the machine showing a front view of the individual type segments and their connections and also showing a front view of the carriage taken on the lines 11—11 of Fig. 6; Figs. 12 and 13 are detail views of the name wheel and its plate; Fig. 14 is a vertical cross-section on the lines 14—14 of Fig. 6 giving a section of the individual type segments and their mountings, and an elevation of the main cam shaft of the machine with its cams and levers; Fig. 15 is a detail front view of the adding wheels and the total type wheels, the latter being in section; Fig. 16 is a horizontal section of the carriage taken just above the hammers showing the carriage removed from the machine but mounted upon a portion of the slide rods; Fig. 17 is a rear view of the cross-over rods and connections; Fig. 18 is a side elevation of one of the key section units or series of keys; Fig. 19 is a cross-section on the lines 19—19 of Fig. 18; Fig. 20 is a horizontal section of the key mechanism taken on the lines 20—20 of Fig. 18, intended merely to show how the shanks of the keys are held by the retaining bar; Fig. 21 is a perspective view of an individual type segment; Fig. 22 is a horizontal section on the lines 22—22 of Fig. 6 showing a part of the carrying mechanism; Fig. 23 is a front view of the front inking ribbon mechanism; Fig. 24 is a side view of the same; Figs. 25—28 are detail views of the counter, Fig. 25 being a bottom view partially in section, Fig. 26 a cross-section on the lines 26—26 of Fig. 25; Fig. 29 is a diagrammatic or skeleton view showing the position of one series of devices in the position they assume when the key has been depressed and the machine operated by means of its main handle; Fig. 30 is a detail showing the action of one of the hammers; Fig. 31 is an opposite view

- of the rear of the machine showing the mounting for a paper roll; Fig. 32 is a top view of said roll and its mounting removed from the machine; Fig. 33 is a view of a slip which has been printed on the machine; Fig. 34 is a view of the duplex paper preferably used in connection with the machine; Figs. 35 and 36 are details of the clearing signal and its operative parts; 5 Figs. 37 and 38 and 39 are details of the carrying mechanism showing successive positions of the parts in the operation of the machine; Fig. 40 is a rear view of the same; Fig. 41 is a detail of the hammer trip of the name plate.
- 10 Before proceeding to describe in detail the various parts of the machine I will briefly state how the machine is operated.
- 15 The operator first depresses such of the keys as represent the number he wishes to print or add upon the machine. The keys depressed are locked in their down position and the operation of any key of a series locks in their up position all the other keys 20 of the same series preventing the depression of more than one key in the same series. He then pulls forward handle 2 secured to a reciprocating rod 3 as far as it will come and then pushes it backward or permits it to 25 return to its backward or normal position. This moves such of the type segments 4 as correspond to the series of keys, in which keys have been depressed, a distance corresponding to the value of the respective 30 keys that have been depressed bringing the one of a series of type 5 carried by the type segment, corresponding to the value of the corresponding key depressed, upon the printing line underneath one of a series of 35 hammers 6, and also adding the same number upon a series of total adding wheels 7 by means of a gear 8, mounted on the type segment 4 and through an intermediate series of adding wheels 9, meshing with gears 40 secured to total adding wheels 7. The movement of handle 2 also causes such of the hammers 6 as are tripped in a manner to be hereinafter described, to print the numbers set upon the printing line upon any 45 suitable record strip, such as the strip of paper 11. The operation of the handle 2 also returns all of the parts to their original or normal positions. The operation of the handle also feeds the paper strip and an 50 inking ribbon. The result of the operation is to print upon the strip the number represented by the keys depressed and to add the same number upon the total adding wheels. If the operator desires to print a 55 total at any time he pushes the carriage 12, which contains the hammers and some other parts of the printing mechanism, backward along the top of the machine until the hammers 6 are over the top of the total adding 60 wheels 7. This operation effects the print-

ing of the total upon the paper strip leaving a space between the total and the items of the account above it as shown in Fig. 33. On the return of the carriage to its forward position the paper is fed to leave a space 70 between said total and the items of the next account. The operator can at any time by moving a reset handle 13 reset the adding wheels at zero.

I will now proceed to describe in detail 75 the different parts of the machine.

The driving mechanism.—This is more particularly illustrated in Figs. 1 to 8 inclusive. In the driving mechanism of my machine I provide a driving member adapted to rotate in one direction only which, as shown, is the main driving shaft 14, a reciprocating member for imparting motion to the driving member, as shown, a rock shaft 15, to which a reciprocating handle 2 is secured and I provide connections between the two shafts for transferring the rocking movement of one into the continuous rotation of the other. These connections are so arranged and adapted that the movement 80 of the handle 2 in one direction will cause the main driving shaft 14 to be rotated a different amount from that imparted to it by the movement of said handle in the opposite direction. I prefer to arrange the parts 85 so that the forward or initial movement of the handle 2 will rotate shaft 14 the greater distance and in the arrangement shown in the drawings that forward movement will rotate shaft 14 two-thirds of a complete 90 revolution, while the return movement of handle 2 to its original position will rotate the shaft the remaining one-third of a complete revolution. The connections shown for 95 this purpose are as follows: 16 is a plate 100 fast to shaft 15. 17 is a plate loosely mounted on the shaft. Slidingly mounted on plate 17 is a slide plate 18 having an extension 19 movable between studs 20 of plate 17. Slide plate 18 is capable of a sliding movement on plate 17. This sliding plate is provided with two reversely acting sets of gearing 21 and 22. These sets of gearing are arranged at different radial distances from the center of the rock shaft 15 and when 105 operative are concentric therewith, one 110 gearing 21 facing outward from the center, the other facing inward. These gears 21 and 22 are so arranged that if the sliding plate is in its outward radial position gear 115 21 will mesh with a gear wheel 23 and gear 22 will be out of mesh, while if the sliding plate is in its inward radial position gear 22 will mesh with the opposite side of gear 120 wheel 23 and gear 21 will be out of mesh. 125 Means are provided for throwing one of these sets of gears into mesh with gear wheel 23 when the rock shaft rotates one way and the other into mesh when it rotates the other way. In sliding plate 18 there is a cam slot 130

24 in which works roller 25 attached to plate 16. The upper part of plate 16 has a tooth 26. Mounted on plate 17 is a pawl 27 which has an extension 28 at the right and an extension 29 at the left. The cam surfaces on these extensions are adapted in the different positions of the parts to strike pins 30 mounted on the side frame of the machine. Mounted on plate 17 are two pins 31, 31 and 10 coacting with these pins but mounted on the side frame are two pawls 32, 32 which are spring actuated and have limiting stop pins 33, 33. Pawl 27 has a pin 34 co-acting with pin 26 of plate 16.

15 The operation of these devices is as follows: In the position shown in Fig. 4, which is the normal position before the operation of the machine, pawl 27 is against pin 30 and tooth 34 is raised out of engagement with tooth 26, pawl 32 is hinged to pin 31; gear 21 is in mesh with gear wheel 23 while gear 22 is out of mesh. The forward movement of handle 2 will cause roller 25 on plate 16 to move forward. The slope of the 20 cam slot 24 is such that this first movement of the handle will move sliding plate 18 inwardly taking gear 21 out of mesh with gear 23 and putting gear 22 into mesh with it on its opposite side. The slight further movement of the handle will cause extensions 28 25 of pawl 27 to free its upper pin 30 and the tooth 34 will drop out from behind tooth 26. Before this takes place plate 16 will have moved forward or to the right a sufficient 30 distance to bring the tooth 34 back of tooth 26. By this time roller 25 will have reached the forward end of slot 24. In this position of the parts roller 25 in slot 24 on one side of pins 26 and 34 will rigidly and positively 35 lock plates 16 and 17 so that forward movement of plate 16 will cause the movement of plate 17 and its connections the same as if the parts formed one rigid structure. This rigidity is essential for the accurate 40 and reliable working of the machine. Further forward movement of the handle will cause gear wheel 23 to rotate in the direction of the arrow which will rotate gear 35 in the direction of its arrow, rotating main 45 driving shaft 14 in the same direction. When handle 2 has reached its forward position pin 31 locks into pawl 32, the end 29 of pawl 27 rides up against pin 30 and frees plate 16 from plate 17 preparing the parts 50 for the return movement. When handle 2 begins its backward movement plate 16, being free from plate 17, roller 25 moves to the opposite or rear end of slot 24 throwing gear 22 out of mesh with gear wheel 23 and 55 gear 21 into mesh and freeing pin 31 from pawl 32 permitting the return of plate 17 and its connections, while the movement of the parts to the rear frees extension 29 from pin 30 and permits pin 34 to drop down- 60 ward. By this time pin 26 has moved to the 65 rear of pin 34 and the latter drops down in front of pin 36. Plates 16 and 17 are again rigidly locked together by means of roller 25 and slot 24 and pins 26 and 34, and plate 17 is carried backward by the movement of plate 16. Attached to plate 16 is a spring 36 anchored to the side frame of the machine. The purpose of this spring is to return the parts to their original or normal positions in case the operator lets go of the handle 70 while on its return or does not push it back far enough. Spring 36 is so proportioned that it will bring the parts back to their original position in such a case. As the parts reach their original positions pawl 32 again 75 locks with pin 31 locking plate 17 and its connections in their original positions and extension 28 on pawl 27 contacts with pin 30 lifting tooth 34 out of engagement with tooth 36 preparing the parts for the next 80 operation of the machine. The reversely acting gears facing in opposite directions and operating upon different sides of the gear wheel 23 when successively in engagement with it, rotate that gear and with it 85 the main driving shaft always in the same direction. The arrangement of these gears 21 and 22 at different distances from the center of the rock shaft enables the main driving shaft to be rotated a greater distance when the handle 2 is moved in one direction than in the other. As shown in the machine these parts are so proportioned that on the forward or initial movement of handle 2 shaft 14 is rotated two-thirds of a complete revolution and one-third of a revolution 90 on the return of handle 2 to its original position. One advantage of this arrangement is that practically the entire work performed by the machine is accomplished by 95 the forward pull of the handle 2. In the machine shown no work is performed on the return of the handle except to return to their original positions a few of the parts 100 of the machine. Through such an arrangement the return spring 36 can be made comparatively very light. Where this spring is made strong as it must be where a considerable part of the work is done on the return of the handle, spring 36 must be made 105 very heavy thus increasing the amount of work to be done by a person in operating the machine. In practice it has been found that the ordinary operator will not push a reciprocating handle backward at least to its 110 full limit, or with the force with which he will pull it forward and that most operators will let the handle go at some point during the return. For these reasons a return spring is essential for practical use. This 115 arrangement, moreover, enables the machine to be made very rapid, accurate and positive in operation. In order that gear 21 may pass in front of gear wheel 35, gear wheel 33 is made of double width so that gears 21 120 and 35 are of equal width. This 125 arrangement, moreover, enables the machine to be made very rapid, accurate and positive in operation. In order that gear 21 may pass in front of gear wheel 35, gear wheel 33 is made of double width so that gears 21 and 35 are of equal width. This 130

and 22 mesh with the front half of it while gear 35 meshes with its rear half as shown in Fig. 3.

Keyboard mechanism.—This is specially illustrated in Figs. 2, 3, 18, 19 and 20. The keyboard consists, as shown, of a bank of keys 1, 1 consisting of eight series each having nine keys. As shown, the keys are of the usual typewriter kind adapted to be operated by being depressed by the fingers, but it will, of course, be understood that any suitable devices of any desired form and construction can be used as keys, and are included under that term as employed in the specification and claims. The keys 1 are mounted in grooves in a casing 37 having one casing for each series of keys which casing and its series of keys and connections form one of the keyboard units. The casings 37 are mounted on rods 38, 38 which pass through openings 39, 39 of the casings. The shaft of each key extends to and is flush with a portion of the casing 37 which is concentric with main driving shaft 14. Each key has a spring 40 to hold it in its upper position and which carries a roller 41, which being in contact with the surface 42 of the casing 37, acts as an operative stop to hold the key in position. The shanks of the keys 30 are held in their slots by the bars 43 to which springs 40 are secured. The back of each key section casing 37 is recessed at 44 in order to give room for the bar 43 of the next section or unit. Running behind the 135 keys and in contact with the rollers 41 of the key shanks is the universal bar 45 mounted upon links 46, and 47 pivoted at the keyboard casing at 48. This universal bar 45 is normally held in its upper position 140 by means of a spring 49 attached to the bar and to the frame. Bar 45 carries a series of pins 50, one for each key shank, each pin being capable of engaging with one or the other of two notches 51, 52 in the key shank 45 according to the vertical position of the key shank. Link 47 has a tooth 53 which co-acts with pawl 54 mounted on the casing 37. 55 is the preliminary or zero stop and is controlled by an arm 56 which is operated by a pin 57 on universal bar 45.

The operation of the parts is as follows: When any key of a series is depressed the roller 41 forces the universal bar 45 of that series downward. As this bar is mounted on 55 two parallel links the whole bar swings downwardly but always maintains a position parallel to its original one. This causes pins 50 to enter notches 52 in the shank of all the keys except that of the key which has 60 been depressed. In the case of that key its pin 50 enters notch 51. The keys are all thus locked in position, the depressed key in its down position, the other keys in their upward position. Pawl 54 engages with tooth 65 53 of link 47 and holds bar 45 in its down-

ward position. The swinging movement of universal bar 45 to the right rocks the arm 56 and lifts the preliminary stop 55 out of its operative position, or in other words, brings it flush with the lower concentric surfaces of casing 37. The toe of the key that has been depressed projects downwardly beyond its concentric portion and acts as a stop in the manner presently to be described, of the mechanism for rotating one of the 75 type segments 4. Preliminary stops 55 in their normal position prevent the movement of the type segments should handle 2 be operated before any keys are depressed. Each pawl 54 is provided with a tail 58 for 80 unlocking the universal bar and permitting the parts to return to their normal position. This operation automatically by the machine will be presently described. It will be noted that the shank of number nine key does not 85 project down to the concentric portion of casing 37. The stop operated part for this key is a stationary plate 59 secured to the casing 37. Otherwise key 9 is like the other keys.

In my above improved keyboard mechanism a single universal bar operates directly to lock the keys in their down or up positions and to unlock them and to control directly the operations of the preliminary or 90 zero stop. By my improved arrangement the keyboard mechanism of machines of the character described herein are very much simplified and the number of parts reduced. The locking and unlocking of the keys by 100 the universal bar is accomplished by means of a single engaging portion on one of these parts and two engaging portions on the other. In the form shown the one engaging part is the pin 50 on the universal bar 45, 105 while the two engaging portions on the keys are the notches 51, 52. This enables the same devices to lock and unlock all of the keys both those that are down and those that are up.

The setting mechanism for the type segments.—This is more particularly illustrated in Figs. 3, 4, 5, 6, 7, 18, 21 and 29. The object of the setting mechanism is to transmit motion from the main driving shaft 14 to 115 the numeral bearing devices, the type segments 4 and from them to the adding wheels and to return these parts to their normal positions. Separate setting devices are provided for each series of keys and the movement of each set is controlled by the keys of the series. Each key when depressed throws a stop into the path of its setting device which stop limits the movement of the setting device in accordance with the 120 value of the key depressed. As the movement of the type segments and their connecting parts is a reciprocating movement and that of shaft 14 a continuous rotary movement, each setting device is provided with a 125 130

part fast on the shaft and a part loose upon it, and a locking piece is provided to normally lock the fast and loose parts together but each lock is thrown out of operative position when it engages a key stop. This throws the loose part from the fast part, the former being locked in the position to which it has been moved. With the loose part are connected the corresponding type segments and connecting parts. The main driving shaft continues its rotation and in the course of the operation of the machine the loose parts are unlocked and returned to their original positions. In the form of these devices shown in the drawings there are loosely mounted on shaft 14 a series of bell crank levers 60. At one end of each of these levers is mounted a locking dog 61 which has projecting lug 62. Lug 62 has a rectangular projection, shown in Fig. 3, adapted to co-act with a surface 63 of a lever 64 fast on shaft 14. The other end 65 of lever 64 forms a counterbalance portion. In the lever 64 is a slot 66. 67 is a spring secured to a vertically extending portion 68 of dog 61 and normally holds the dog in the position shown in Fig. 6 with surfaces 62 and 63 in contact. Portion 68 has a projection 69 extending at right angles to it adapted to be engaged with notches 70 of a locking plate 71 secured to casing 37. 72 is a stop pin for limiting the movement of dog 61. When shaft 14 is rotated lever 64 forms contact with surfaces 63 and 62 pushes bell-crank lever 60, to which locking dog 61 is secured, ahead with it, thus rotating bell-crank lever 60. This movement of the latter continues until the nose of locking dog 61 engages either the preliminary or zero stop 55 or lower end of the shank of any key that has been depressed, which shank in that case acts as a stop. This contact slightly rotates dog 61 on its pivot, moves pawl 62 away from contact with surface 63 of pawl 64 and brings it opposite slot 66 in lever 64, permitting lever 64 to continue its rotation with shaft 14 but preventing higher rotation of bell-crank lever 60. The slight rotation of dog 61 also throws rectangular portion 69 into one of the notches 70 of locking plate 71 thus positively locking bell-crank lever 60 and its connections in a fixed or rigid position. In a machine of the character shown and described herein in which the parts must necessarily have great rigidity of movement, this positive locking is of great importance. It permits the rapid operation of the machine and at the same time insures absolute accuracy and certainty in operation. The means shown for returning the levers 60 to their original position consists of the following: Attached to each bell-crank lever 60 is a link 73 pivoted to a plate 74 having a downwardly projecting tooth 75. Plate

74 is loosely mounted on shaft 76. Fixedly mounted on shaft 76 are two arms 77 carrying a universal bar 78 adapted to co-act with the teeth 75 of the different plates 74. On the outside of the machine (see Fig. 7) 70 mounted on main shaft 14 is a cam 79 which acts on the cam roller 80 of a bell-crank lever 81 pivoted at 82 to the framework, the roller 80 being held against the cam by means of spring 83. Attached to this bell-crank lever 81 is a link 85 fixed to shaft 76. These parts stand normally in the position shown in Fig. 7. Immediately upon the beginning of rotation of shaft 14 (in the direction of the arrow in Fig. 7), roller 80 will drop down to cam surface 79 carrying universal bar 78 away from teeth 75 thus leaving bell-crank lever 60 in a position free to rotate. Later on in the rotation of shaft 14 cam 79 will begin gradually to move 85 roller 80 upward and thus gradually to swing universal bar 78 slowly to the right as viewed in Fig. 6. During this movement it will collect the teeth 75 and move them gradually to the right to their original positions, as shown in Fig. 6, thus returning bell-crank levers 60 to their original positions. By this time the levers 64 fast on shaft 14 have completed one revolution and the parts will occupy the positions shown 95 in Figs. 6 and 7 ready for the next operation.

The type segments and connecting parts.—These are specially illustrated in Figs. 6, 11, 14, 21 and 29. Each type segment 4 is 100 connected to one of the rock levers 60 through a link 86 pivotally connected with arm 87 which forms a portion of the type segments. These type segments may be made of any suitable form. As shown they 105 are made with a body 88 forming a part of a cylinder and a segment 89 carrying type 5 and ratchet teeth 90 and a segment 91 having gearing 8 meshing with intermediate adding wheels 9 as already described. The 110 different type segments are arranged with their cylindrical portions nested together in the well known manner. By this arrangement the arms 87 can be brought opposite the different bell-crank levers 60 while the type 115 segments can be arranged close together so as to be capable of printing a column of figures of the character shown in Fig. 33. The type segments are preferably arranged so that the zero type will normally be slightly off 120 the printing line, as shown, slightly in advance of that line and the segment will then be moved to bring the zero to the printing line and will then be moved to bring upon the printing line the type represented by 125 the key depressed. I also mount the type segments movably so that they can be swung in a curved path to mesh with the adding wheels. In the form shown in the drawings the type segments 4 are mounted on the main 130

shaft 92 which shaft is carried by arms 93, 93 pinioned to a rock shaft 94. To the rear of main driving shaft 14 is a cam shaft 95, which is driven by main driving shaft 14 through gear 96 on the latter shaft (see Fig. 7) through intermediate gear 97 and gear 98 on shaft 95 so that the latter shaft rotates in the same direction and in unison with driving shaft 14. Mounted on shaft 95 is a race cam 99 in which runs a cam roller 100 mounted on arm 101 rigidly secured to rock shaft 94. Cam 99 consists of an up-raised portion 102 and a long portion 103. Co-acting with ratchet 90 are a series of pawls 104 pivoted on a stud 105 and having a downwardly extending portion 106 which normally rests against a key or feather 107 mortised into a shaft 108.

The operation of these parts is as follows: 20 When the machine is at rest the parts occupy the position shown at Fig. 6. On the first start of the machine shaft 108 is rotated slightly, by means to be hereinafter described, so as to free the depending portions 25 106 of the pawls permitting the pawls 104 to drop into engagement with the ratchet teeth 90. Just before this happens portion 102 of race cam 99 raises roller 100 rocking shaft 94 and rocking arms 93. This rocking 30 movement is sufficient to carry shaft 92 and the individual segments slightly to the right, as viewed in Fig. 6, so that the zero or first numeral on each type segment will be upon the printing line or in line with the hammers. When this position is reached the 35 pawls 104 drop into the first tooth of ratchet 90 holding the type segments momentarily in this position of alinement. A further movement of the main driving shaft moves 40 the rock levers 60 until they are stopped either by the preliminary stops 55 or the depressed shanks of the keys. This movement of the rock levers 60 is communicated to the type segments, which type segments 45 are moved the distance corresponding to the value of the key that has been depressed in its series bringing the proper type upon the printing line. Fig. 29 illustrates the position of the parts taken in such operation 50 when the 8 key has been depressed and the main driving shaft has been rotated far enough to bring dog 61 of its series into engagement with the depressed shank of key 8. This swinging movement of the type 55 segments to the right and slightly downward enables the teeth of gear 8 to mesh with the gear teeth of wheel 9 always with certainty and accuracy and without any binding of the teeth. This is assisted by 60 commencing the upward rotation of the type segment just at or slightly before the intermeshing of the two gears. The movement of gear teeth at that moment is a combined one and more effectually insures against any 65 binding of the teeth of the two gears.

Adding mechanism.—This is more particularly illustrated in Figs. 5 to 8, 22, 29, 37 and 40. The intermediate adding wheels 9 are loosely mounted on a shaft 109 mounted in the sub-side frames 110 and 111 of the 70 machine and are restrained by pawls 318 secured to the framework. Each wheel 9 is provided with forty teeth and each gear 10 with which it meshes is provided with twenty teeth. Below the adding wheels 9 75 are a set of carrying wheels 112 loosely mounted on the shaft 113, supported in the sub-side frames. Each carrying wheel 112 has thirty teeth and is provided with three carrying pins 114, spaced one hundred and 80 twenty degrees apart. These co-act with the carrying set-up levers which levers carry the carrying pawls 116. Each set-up lever 115 has a rearwardly extending portion 117 which co-acts with locking levers 118. Set-up levers 115 are loosely mounted on a stud 119 and locking levers 118 are loosely mounted on stud 120. Carrying pawls 116 are loosely pivoted to a downwardly extending portion 121 of set-up levers 115 and are 85 normally held with the left hand portion upward through spring 122. Carrying pawls 116 have a rear portion provided with a right angled portion 123 which are adapted at all times to co-act with one of a series of pins 124 mounted in a spiral fast on circular plates 125 secured to rock shaft 126. 127 is a plate mounted on rock shaft 128, there being one of these plates for each carrying wheel. Each plate 127 has a carrying rack 100 139 mounted upon its plate by means of studs 130, 130 secured to plate 127 passing through slots 131 in the carrying rack, each rack being held normally in its upward position by means of a spring 132 secured to 105 the plate and rack. Carrying rack 139 is provided at its upper end with teeth 133 which at times mesh with the teeth of carrying wheels 112. Rack 139 is provided with a lip 134 with which the toe of its corresponding carrying pawl 116 is at times adapted to engage. Mounted on a rock shaft 135 are two arms 136 which carry a universal bar 137, which on rotation of rock shaft 135 comes against the upper surface 110 138 of locking levers 118. Upon shaft 120 are mounted two plates 139 which extend downwardly and at their lower ends 140 are grooved to conform to the surface of the disks 125. Extending between the two 115 plates 139 is a fixed stud 141 which co-acts at times with a rearwardly extending arm 142 of lock levers 118. A spring 143 normally holds lock levers 118 in the position shown in Fig. 6. A spring 144 normally 120 holds each set-up lever 115 in the position shown in Fig. 6.

The operation of the adding and carrying mechanism is as follows: The movement of gear 8 is imparted through intermediate 130

adding wheels 9, gear 10 to total adding wheels 7 adding on each operation of the machine to the total already standing upon those wheels the number that is set up on the printing line. The intermediate adding wheels 9 also rotate the carrying wheels 112 a similar number of teeth. As soon as this addition takes place cam roller 100 runs off the high portion of cam 102 and the type segments are moved out of engagement with adding wheels 9. When carrying wheel 112 has been moved nine units one of the pins 114 is immediately next and to the left of the toe of set-up lever 115. Upon the next movement of wheel 112 pin 114 will rotate lever 115 slightly to the right. This rotation will move the rightangled portion 145 on the right end of lever 115 from the position it occupies in Fig. 37, which is the normal position, into the position shown in Fig. 38. In the former position the rightangled portion 145 lay against surface 146 of lock lever 118 but in the position to which it is moved it lies against the surface 147 slightly cut away thus locking lever 115 in its retracted position. 148 is a lip on lock lever 118 to prevent lever 115 from over-throwing. The parts of my improved machine operate so rapidly that the momentum of levers 115 would be apt to throw the end 147 over the lower part of lever 118 if it were not for this lip 148. Should such an over-throwing occur it would block the machine and render it inoperative. Lip 148 also aids in the return movement of the parts to insure the quick return of lever 115 to its original position. If desired lip 148 can be continued upward still further or be joined with the projecting portion of lock lever 118 lying just above it so that there will be no opening upon which the right hand end of 115 can possibly be thrown. The position of lever 115 and its connecting parts immediately after the above carrying operation is shown in Fig. 29. The rotation of set-up lever 115 moves the carrying pawl 116 to the left and upward bringing its toe over lip 134 of carrying rack 139 and also bringing the rightangled projection 123 into line with the pins 124 of the spiral. Immediately after this has taken place a cam 149 (see Fig. 5) on cam shaft 95 acts on the cam roller by a lever 150 which is fast on shaft 128 and rocks this sufficiently to throw plates 127 and carrying racks 139 to the right bringing teeth 133 into mesh with the wheels 112. This brings lip 134 under the left hand end of pawl 116. It will be understood that this lip 134 extends laterally so that the pawl 116 with which it engages will be the pawl of the next lower numerical order. The adding helix in the continued operation of the machine is rotated so that the pins 124 will engage with right angled portions 123 of such of the pawls 116 as have been moved in the position shown in Fig. 38. This will rotate pawl 116 on its pivot and through lip 134 will force rack 139 downward moving carrying wheel 112 of the next higher order one unit. Where, however, a pawl 116 has not been thus set but is in its normal position, shown in Fig. 37, the pin of this spiral will pass inside of the projection 123 and will not affect pawl 116 in any way. The carrying helices are rotated by means of the following devices: Mounted upon cam shaft 95 (Fig. 7) is a cam 151 which acts on the cam roller 152 mounted upon lever 153 pivoted to the frame work at 154. Pivoted to lever 153 is a link 155 pivoted at its other end to an arm 156 mounted upon rock shaft 157. A spring 158 normally holds arm 156 in its rearward position. Referring now to Fig. 8 it will be seen that shaft 157 which extends inwardly and has its inner end mounted in the side frame 110, carries a segment 159 which in turn meshes with a pinion 160 secured to adding helix shaft 126. Shaft 126 is thus rotated through an arc sufficient to cause adding spiral pins 124 to pass successively by their corresponding carrying pawls. 161 is a binding pin which fastens or holds adding spiral plates together. At the last moment of rotation just before cam 151 has ceased to act this binding pin comes into contact with the end 162 of plates 139. This moves plates 139 to the rear sufficiently to lift bar 141 against portions 142 of the locking levers 118 rocking those levers to the left so as to unlock the carrying levers 115. This returns the various parts of this operation of the mechanism to their normal and original positions. The pins 124 of the spiral on their return movement pass by projections 123 without touching them.

In order to insure the accurate return of the carrying plates to their normal or original positions in case the springs do not operate properly I preferably employ means for positively returning them to such position. The devices shown for this purpose are as follows: 440 is a bar extending under the entire set of carrying racks. It is supported on an arm 441 pivoted at 442 under the keys and carrying at its other end a cam roller 443 operated by a cam 444 on cam shaft 95. Away at the end of the operation of the machine this cam positively pushes up the racks to release them instantaneously upon the starting of the machine.

Resetting mechanism.—This is specially illustrated in Figs. 6, 7 and 8. 13 is a reset handle for the purpose of resetting the adding wheels whenever desired. The arm 163 to which this handle is connected is secured to a short shaft 164: (Figs. 2 and 7) on this shaft is mounted a rocking arm 165. Pivoted to this is a link 166 pivoted to an arm 167, the latter mounted upon rock shaft 132.

135. Pivoted to a universal bar 168 extending from between the two arms 136 are a series of reset levers 169, one for each of the adding wheels 9. Each reset lever has a 5 cam slot 170 through which passes a stationary stud 171 fixed in the sub-frames 110 and 111. Each reset lever 169 has a toe 172. On each adding wheel 9 are a series of pins 173 spaced ten teeth apart. The toes 10 172 of the reset levers are normally out of the path of pins 173. When the reset handle is turned by means of the connections above described the reset levers are thrown to the left and the cam slot 170 and the fixed stud 15 171 cause the toes 172 to be moved up into the path of rotation of the pins 173 and to be then moved circumferentially along that path to the left as shown in Fig. 6. In this movement the toes 172 pick up the pins 173 20 and move wheels 9 until the pins 173 are in the position occupied by them when the wheel is in its normal or zero position. This movement also moves the total adding wheels back to their zero position and brings 25 the pins 114 on carrying wheels 112 back to their original zero positions. The cam slot 170 is so shaped that the first movement of toe 172 is substantially a vertical one, while the second movement carries the toe in a 30 curved path concentric with shaft 109. This operation collects the pins 173 in whatever position they may be and returns them to the zero position. After reset handle 13 has been pulled forward to reset the adding 35 mechanism it and its connecting parts are returned to their original positions by means of a spring 174 secured to arm 165. The forward movement of arm 136 has carried forward the universal bar 137, bringing it 40 into contact with the upper portion 133 of the locking levers 118 pushing them forward and releasing the carrying levers 115 in the same manner that the bar 141 released them. This operation returns the carrying mechanism to its original position. The stud 175 45 (Fig. 9) acts as a binding stud for the two arms 136.

Interlock between the main handle and the reset handle.—This is more particularly 50 shown in Figs. 8 and 35. It has been found important in practice to interlock the main handle with the reset handle so that only one of them can be operated at a time; when one has been started the other will be locked 55 until the first one has completed its work. This may be accomplished in any desired manner. The devices shown in the drawings for this purpose are as follows: Mounted upon the main handle shaft 15 is a segmental plate 176 and upon the reset handle shaft 164 is mounted a corresponding plate 177, the direction of rotation of the shafts 15 and 164 is indicated by the arrows in Fig. 8. Referring now to Fig. 35 in which 60 65 these two plates are shown in section to-

gether with the arrows indicating the direction of movement, there is mounted upon the base of the machine a bracket 178 which forms the inner bearing for the shaft 164. Passing from the other part of the bracket 70 is a cylindrical opening 179 in which is loosely mounted a hard steel stud 180. Each of the plates 176 and 177 has in it a depression 181 adapted to receive the rounded end of stud 180. The length of stud 180 is such 75 that it occupies the entire opening 179 and one of the cuplike depressions 181. These cuplike depressions are made slightly cam 80 shape. If either plate 176 or 177 is revolved slightly in the direction of its arrow this 85 cup will force the steel stud 180 out of the cup and into engagement with the other cup locking the plate of the latter. This locking will remain effective until the handle connected with the locking plate has completed 90 its full movement. It will thus be seen that the interlocking mechanism is under the control of both the main handle and the resetting handle and is thrown into operation by the handle that first starts its 95 movement.

Release and repeat keys.—These are specially illustrated on Figs. 3, 4, 6, 7 and 18. The release key is provided in case an error should be made in depressing the keys to 95 permit the keys to be returned to their normal positions without operating the machine. A repeat key is also provided to permit the same number to be printed and added successively a plurality of times without again 100 depressing the keys. The mechanism for these purposes shown in the drawings consists of the following: 182 is a wheel fast on shaft 14 at the extreme left of the machine. This wheel is provided with a cam 183 having a cut away portion as shown near the top in Fig. 6. 184 is a pin mounted in the side of wheel 182. On a rock shaft 185 which extends between the side frames of the machine is mounted a universal bar 186 carried by the side arms 187 (Fig. 3); also mounted upon its rock shaft 185 is a lever 188, held normally in the position shown in Fig. 6 by means of a coil spring 189 (Fig. 3) coiled around shaft 185 and having one end extending under universal bar 186. This arm 188 has a right angular extended portion 190. This is cam shaped and upon it acts pin 184. Upon the right hand end of shaft 185 is mounted an arm 191 which co-acts with a 110 pin 192 mounted upon the shank of repeat key 193. A spring 194 holds this key normally in its upward position. The arm 188 has an extended portion 195 which co-acts with the pin 196 (Fig. 7) mounted on the 115 shank of the release key 197. This release key is held in a normal upright position by spring 198. It will be noted by reference to Fig. 6 that the universal bar 186 lies contiguous to the pawls 58 of the keyboard 120

mechanism. Upon the arm 188 is mounted a pin 199 (Fig. 3) which extends over and co-acts with the arm 187. The operation of the above mechanism is as follows: One or more keys having been depressed the universal bars of the series containing the keys depressed are locked in their down position and the tails 58 corresponding therewith occupy their rear position. If it is desired to release the keys that have been depressed pin 199 forces arm 187 downward and rocking universal bar 186 downward and forward against the pawls 58 of the keys that have been depressed. This will unlock the universal bars from their connections permitting them and their connections to return to their normal positions. This release of the universal bars through their tails 58 is also accomplished at the end of each operation of the machine by pin 184 striking against the rear end of arm 188 and moving pin 199, rocking universal bar 186 downward and to the left in the same manner. If, however, it be desired to print or add the same number a second or any successive number of times, this can be done without again depressing the same keys. In that case the repeat key 193 is depressed and as long as it remains down and the main operating handle is turned the same number will be printed upon the recording strip and will be added upon the adding wheels. The depressing of key 193 brings shoulder 200 of its shank under pin 201 (Fig. 4) in which position the repeat key is held by spring 194 and locked in its down position, where it will remain until the operator releases it by pulling the key slightly forward to disengage shoulder 200 from pin 201. The depression of repeat key 193 causes pin 192 to press upon arm 191 of rock shaft 185 rocking the shaft in such a direction that the cam portion 190 of arm 188 is depressed so that pin 184 on wheel 182 will pass entirely over it without striking it. The main driving handle can therefore be operated without releasing the keyboard mechanism.

It is found important to prevent the release of the keys that have been depressed by the operation of the release key after the main operating handle has started in its movement. In order to accomplish this the wheel 182 is provided with the rim 183. This rim prevents the raising of arm 188 with its accompanying cam 190 by means of pressure upon the release key 197 and the consequent release of the keyboard mechanism. The only position in which the release key can be operated is when the machine is at rest with the opening in the rim 183 at the top of the wheel in the position shown in Figs. 3 and 6.

Printing mechanism.—This is specially illustrated in Figs. 1, 2, 4, 5, 6, 9, and 16.

Mounted on the top plate of the machine

are sliding rods 203, 203 (Fig. 2) fixed in bosses upon which rods the carriage 12 is mounted. This carriage has two sliding plates 205 adapted to slide upon rods 203 upon which is hinged the housing of the hammer mechanism. These two plates are attached at the forward end by the rods 206 which pass through links 207 and are held in position by screws 208. At both the right and left of the machine and hinged to the plates 205 are side housings 209 which include the part of the hammer operating mechanism which goes into contact with the hammer trips as will be explained herein-after. In the forward part of the carriage is mounted a shaft 210 carrying the main feed roller 211. On this shaft but inside of the right hand side housing is a spur gear 212 and a ratchet wheel 213. In the right hand housing above shaft 210 is a short shaft 214 (Fig. 4) carrying a gear 215 meshing with gear 212. Shaft 214 has upon its upper or right-hand end outside of the casing a knurled wheel 216 (Figs. 1 and 2). Referring now to Fig. 6, mounted in the arms 217 pivoted at 218 and between the side housings is another feed roll 219. This roll is held normally in contact with main feed roll 211 by means of spring 220. The forward end of arms 217 rest upon a rock shaft 221 which extends between and through the two housings and has upon its right hand end outside of the casing a thumbpiece 222 (Figs. 1 and 2); coacting with the forward end of arms 217 and in shaft 221 is a pin 223 extending outward from both sides of shaft 221. At the rear of the carriage underneath the hinged rod 224 is a roller 225 which is held up into position against the hinged rod 224 by means of a spring 226 mounted on a block 227 adapted to hinge rod 224. Referring to Fig. 16 it will be seen that on one side of each of the blocks 227 is a coiled spring 228 encircling rod 224 secured at one end to block 227 and passing at its other end under one of the side housings at the point 229. These springs exert an upward pressure upon the carriage and when permitted will raise the forward end of the carriage into the position shown in Fig. 5. Mounted on the inside of each of the right and left hand housings at the forward end is a small pawl 230 (Fig. 6) which pawl is pivotally mounted on the carriage at 231 and held in normal locking position by the spring 232. The lower end of pawl 230 engages a pin 233 fixed to the stationary bar 206. The upper end of pawl 230 co-acts with the other end of pin 233 which projects to the left through bar 221 and has a portion 234 for limiting the rotation of rock shaft 221. Mounted between the two side housings is an intermediate paper guide roll 235 which is idle and serves merely to hold the paper down

against the type plate. It will be noted that if the knurled wheel 216 be turned, the lower feed roll will be driven by the gearing 214 and 212 in either direction; also that the pressure in one direction on the thumb piece 222 will serve to separate the feed rolls by releasing roll 219 so as to permit the paper to be passed through between them, whereas motion of the thumb piece in the other direction will cause pin 223 to act on the cam locked surface of pawl 230 forcing it forward and releasing the pawl from engagement with pin 233, whereupon springs 228 will cause the carriage to rise into the position shown in Fig. 5. On restoring the carriage to its normal position pawl 230 will act as a lock and hold it in its downward position. Mounted upon the inside of the right-hand housing is a pawl carrying plate 236 pivoted at 237 in the frame work of the carriage. This plate carries a pawl 238 on its forward end which acts upon ratchet wheel 213 to rotate shaft 210 and feed forward the paper. The rear end of plate 236 has two parts, one a downwardly projecting portion 239, which portion has its lower surface flush with the lower surface of the carriage, and a portion 240 which has two cam surfaces 241 capable of co-acting with pin 242 affixed to the type plate. Pivoted to the right-hand main side frame of the machine at the point 243 is an operating plate 244 which extends through an opening of the side frame and then upwardly until it is flush with the type surface at the point 245 where it is directly in line with the downwardly extending portion 239 of the plate 236. At the lower end of the operating plate 244 and pivoted at 246 is a connecting link 247 extending downwardly and attached to an arm 248 bearing a cam roller 249 bearing against a cam 250 mounted upon the main cam shaft 95. It will be seen that when cam 250 comes into operative position it will raise the arm 248 and link 247 and will push up the surface 245 into contact with surface 239 thus rocking plate 236 upon its pivot and causing pawl 238 to move in a downward direction and through gear 212 to rotate shaft 210 and main feed roll 211 thus feeding forward the predetermined amount of paper. This feed takes place at the very beginning of the operation of the machine and is practically the first thing that happens. Normally the paper used is a short paper and is pushed through the guide rolls at the rear of the carriage and underneath the free roll 235 under the hammers, around the lower feed roll and up in between the two rolls as shown by the dotted lines in Fig. 6. If desired the paper may be passed after going from the feed rolls underneath a shoulder piece of metal 251 which may be used as a stationary knife in order to tear off the amount of

paper needed. If preferred a roll of paper may be used and in Figs. 31 and 32 a roll 252 is shown mounted in brackets 253. From the roll the paper passes through the machine as already described. Preferably I use individual hammers for the different type segments. These are shown in Fig. 16. In the machine shown in the drawings eleven hammers are required. The two right-hand hammers, as viewed in Fig. 16, 75 being for the cents and these are preferably secured together and operated as one. The extreme left-hand hammer shown in Fig. 16 is for the name wheel and, as shown, is preferably made wider than the others. 80 The hammers are operated through the main driving mechanism of the machine by means of trips, these trips engaging with projecting portions or toes connected with the hammers. In my preferred form the 85 trips of all of the hammers are always operative but only those trips engage with the hammer toes which are moved into operative position through the operation of a key of the corresponding series of keys. I will 90 now proceed to describe this mechanism. Situated inside the right-hand housing of the carriage are the five lower projecting portions or toes connected with the hammers and in the left-hand housing the four upper 95 hammer toes and that of the name wheel are arranged. The cents are always printed together and the two cents hammers are therefore operated together and mounted in a common operating block 254. This operating block together with the other operating blocks to which the hammer handles are secured are pivotally mounted upon stationary shaft 255, which shaft extends across the machine through the side housing, being held in position by screws 256. Each hammer and hammer block is arranged with a projection or toe 257 adapted to be tripped to operate the hammer in a manner presently to be described. These toes form the 100 lower part of rocking piece 258, each loosely mounted on shaft 255 and each mounted to its hammer block by a cross-over rod 259. Five of these toes 257 are arranged in the right-hand housing and five in the left as 110 shown in Fig. 16. The cross-over rods are arranged as shown in that figure, the cents one connecting with the piece 258 at the left in the right-hand housing, the dollar with the next piece 258 to the right and so 115 on, the cross-over rod 259 of the name plate hammer communicating with the right-hand piece 258 in the left-hand housing, the block 254 of the higher numeral hammer with the piece 258 next to the left and so on. 120 These cross-over rods are for convenience arranged in a spiral manner as shown in Fig. 6. Each piece 258 has a spring 260 for holding it in normal position, the springs being attached to a spring bar 261 130

(Fig. 4). This spring bar consists of a small frame 262 mounted upon a shaft 263 which shaft extends across through the housing. It will be understood that there are two such spring bars one on each side of the machine. Each spring bar has connected with it a handle 264 to move the spring bar into various positions. 265 are notches in the covering 266 of the carriage (Fig. 2). 5 These notches are made by cutting an opening 267 in the top covering leaving the prongs 268. These cuts form a resting place for handle 264. Any number of notches may be provided. By varying the position 10 of the handle 264 in the notches the tension of the springs 260 can be regulated. The hammer toes 257 project downward to a point nearly flush with the depressed surface of the top plate as shown in Fig. 4. 15 In an opening 269 in the top plate project upward a series of trips 267 projecting upward from sliding trip plates 271. These trip plates and the trips are adapted to have a reciprocating forward and backward movement. Each trip plate is mounted 20 upon a tilting plate 272 pivotally mounted upon a stud 273 secured to the side frames. Each plate has a cam slot 274 at its forward end in which rides a pin 275 secured to a 25 plate 276 pivoted on a stud 277. Each tilting plate 272 has slots 278 in which work pins 279 secured to trip plate 271 allowing a sliding motion of the trip plate upon the tilting plate. The lower part of trip plate 30 35 40 45 50 55 60 65 70 75 80 85 90 95 100 105 110 115 120 125 130 271 is bifurcated to allow the head 280 of operating lever 281 to rise between the two projecting parts of the trip plate to give a forward and backward movement to the trip plate. Lever 281 is pivoted on a small shaft 282 which on the side of the side frame has mounted on it an operating arm 283. Connected to arm 283 is a link 284 pivoted at the bottom to a lever 285, the lever being provided with a cam roller 286 bearing against a cam 287. It will be seen that the action of cam 287 when it becomes operative is to depress lever 285 and through the above connections rock lever 281 to the left to move trip plate 271 in a horizontal direction along its slots.

In the normal operation of these parts all of the trip plates 271 are reciprocated forward and backward at every operation of the machine. It will be noted that normally, 55 that is, when no key of the corresponding series has been depressed, trip 270 of the trip plate is too low down to engage with its corresponding toe 257. If a key in the series, however, is depressed it will operate 60 to rock set plate 276 to the left or forward and will tilt the rear end of tilting plate 272 upward raising toe 267 of trip 271 high enough to engage with its corresponding toe 257. In this position of the parts the forward travel of trip plate 271 and trip 267

will force toe 257 to the left rocking plate 258 and through each cross-over rod raising the hammer upward. When trip 267 passes toe 257 the hammer will be brought down to deliver the printing blow. The handle of each hammer is preferably pivoted at 288. Secured to projecting portions of each is a compressed spring 289 which normally holds the hammer upward in the position shown in Fig. 6. The object of this is 75 to provide for the rebound. Fig. 30 illustrates the position of the hammer and its toe and the trip plate and tilting plate in the act of printing. The full lines represent the position of the parts immediately before 80 contact is made between the trip and the toe, and the dotted lines the position of the parts at the moment when the trip is about to snap under from the toe. The operating head 280 of lever 281 is wide and extends 85 through the entire set of trip plates. The means by which the depressed key rocks setting plate 276 to the left will now be described as embodied in the form shown in the drawings. These are particularly illustrated in Figs. 3, 4, 6, 11 and 17. Each setting plate 276 is held by a spring 290 normally locked to the rear as shown in Fig. 4. On reference to Fig. 6 it will be noted that each arm 87 carries a sidewardly extending 90 roller 291. Each of these rollers coacts with an extension 292 connected with a plate 293 pivotally supported on a fixed stud 294. Each plate 293 is arranged alongside of its corresponding arm 87. Each plate 293 is 100 connected with its corresponding setting plate 276 by means of a cross-over rod 295 in the same manner as the hammer blocks are connected to the plates 258 and the cross-overs are arranged spirally in the same manner and for the same purpose. Fig. 17 gives a rear view of these cross-over rods. 296 are pins projecting each from the face of one of the setting plates 276 across the face of the plate of the next lower numerical 110 order. The object of this is so that the movement of the setting plate of a higher order will move all of the setting plates of lower orders in the operative position so that the depressing of a key of any order 115 will not only cause its own hammer to be operated but the hammers of all lower orders also to be operated. The cross-over rods 295 shown at the bottom of Fig. 17 are shown as having at 297 an over-lapping 120 joint. The rod 295 at the right of that figure, which is a rod running from the lowest numerical setting plate of the high side of the machine, over-laps the other rod 295 which is connected with the highest numerical setting plate on the low side of the machine for the purpose just described. Each extension 292 has a cut away or depressed portion 298 (Fig. 6).

The operation of the above parts is as 130

follows: At the time that the pawls 104 have dropped into the first notch of the ratchets 90 of type segments 4, each roller 291 has swung the corresponding extension 292 slightly to the right and has entered the cut away portion or depression 298. If a key of the corresponding series has been depressed the arm 87 rocks still farther and in that case its pin 291 moves 10 extension 292 slightly to the right and moves down the curved outer surface 299 on extension 292. Extension 292 and its outward curve 299 are so arranged that in this position of the parts the further downward and rearward movement of roller 291 will follow the line of the curve 299 that now being concentric with shaft 92 so that no further movement will be imparted to plates 293 and their corresponding setting 15 plates 276. Such further contact with roller 291 with extension 292 simply serves to hold plates 276 in their set position. But the rearward movement of extension 292 imparted to it when roller 291 passes out 20 from cut away portion 298 upon surfaces 299 is sufficient to rotate plates 293 and setting plate 276 enough to tilt plates 272 as above described. In this manner the depression of a key in any series sets its trip 25 267 into operative position ready for the actuation of its printing hammer upon the operation of the main operating handle and it also sets the trips of all hammers of lower numerical orders. Immediately in the rear of 30 the front hammer trips are a set of hammer trips for actuating the hammers to print the total on the adding wheels. For convenience these trips will be spoken of as the total hammer trips. There is, of course, one 35 of these total hammer trips 300 for each wheel 7 of the adding series. In the form of machine shown in the drawings where there are only eight type segments, only eight trips 267 are required, but two extra 40 adding wheels are used and accordingly two extra hammer trips 300 are required, or in other words, ten trips. Each hammer trip 300 is pivoted at 301 to a tilting plate 304 and is provided with a spring 302 to hold it 45 against the stop 303 on the plate 304. The plates 304 are pivoted to a stud 305 secured to the frame work, and provided with a slot 306 in which runs a pin 307 attached to a setting-up plate 308 pivoted at 309 with a 50 stud secured to the frame work. Each total trip is slightly depressed below the printing level exactly like trip 267 and projects upward into an opening 310 in the top plate 55 at the rear of the machine. A rocking forward motion of plate 308 will raise trip 300 into operative position ready to engage its corresponding toe 257 and cause the operation of its hammer when the carriage is pushed backward to the rear of the machine. 60 65 A total can be taken at any time by pressing

the carriage backward along the side rods 203. The purpose of the two cam parts 241 of the plate 236 is to make one of the surfaces 241 of the plate 236 ride up on stationary pin 242 affixed to the type plate, and the 70 purpose of the other surface 241 to ride up on the same pin 242 on the forward motion of the carriage so that on both the rear and forward movement of the carriage the paper will be fed and a space left above and below 75 the total as printed on the paper. Preferably the total is printed in a colored ink to distinguish it from the different items. The spaces above and below the total are illustrated in Fig. 38. Plates 308 are set up, as 80 shown in the drawings, by means of the following devices: Mounted upon a shaft 311 near the rear of the machine are a series of bell-crank levers 312. Pivoted to each is a link 313, which in turn is pivotally attached 85 to a plate 314. Each plate 314 has a cross-over rod 315 connecting it with corresponding setting-up plate 308. These cross-over rods are arranged spirally in the same manner as the cross-over rods of the set up 90 plates 276. A rear view of these cross-overs will be found in Fig. 9. One arm of the bell-crank lever 312 has a nose 316. These parts are frictionally held and will set in whatever position they are moved to. The 95 nose 316 is adapted to co-act with pins 173 of adding wheels 9. When wheels 9 are at their zero position one pin 173 is immediately above and in contact with nose 316. The first movement of the adding 100 wheels 9 from zero to one causes the pin 173 to rock nose 316 of lever 312 slightly to the right (Fig. 6). This movement is sufficient to rock set-up plate 308 sufficiently to the left (Fig. 4) to raise trip 300 into operative 105 position. The positions of pins 173 on wheels 9, as shown in Fig. 6, is not the zero position but represents some position to which the wheels have been moved after amounts have been added on the machine. 110 It will be seen from the above that the initial movement from zero to one of any of the adding wheels 9 will set its corresponding hammer trip where it will remain in such position until the adding wheels are 115 reset at zero. These trips and their connecting parts are returned to normal position, when the resetting handle is turned, by means of a universal bar 175 mounted on two arms 319 fast on shaft 168 striking 120 bell-crank lever 312 moving nose 316 back into operative position and restoring all of the connecting mechanism to their original positions.

Clearing signal.—This is specially illustrated in Figs. 4 and 36. It has been found advisable in practice to have a signal to indicate the condition of the machine, that is, whether it is in the zero or non-operated condition or whether numbers have been 125 130

printed and added. For this purpose I provide a signal which I will speak of as the clearing signal. As shown it consists of a curved plate 320 pivotally mounted on a 5 stud 321 and opposite an opening 322 in the front casing of the machine. On this signal appear the words "Clear" and "Not clear". When the word "Clear" stands opposite the opening it means that the machine has not 10 been operated but stands in the zero position. This signal is mounted immediately in front of the cents setting plate 276. No matter what the first amount is that is set up the cents hammer setting plate 276 always 15 moves in order to print at least the zeros of the cents column. In this rocking forward movement the cents plate 276 plays against an arm 323 connected with the segment carrying the clearing signal. This 20 rocks the plate downward bringing the words "Not clear" opposite the opening of the machine. The signal is positively held in any position to which it is moved by means of a pin 324 on an arm depending 25 from and forming part of the plate bearing segment and a notched spring 325 provided with two notches (Fig. 4). When the machine is reset at zero the signal is restored to its clear position by means of a link 326 30 pivoted to a bell-crank lever 327 mounted in the rear of the machine. Upon the shaft 135 of the resetting mechanism already described is mounted just opposite of the right-hand sub-frame 111 a disk 328 which carries 35 a pin 329. In the return of the resetting shaft this pin restores the clearing signal to its clear position.

Name wheel and its operating mechanism.—These are particularly illustrated in 40 Figs. 2, 3, 7, 10, 12, 13, 14 and 33. 330 (Fig. 3) is a wheel for printing names such as "Note", "Check", etc., see Fig. 33. As shown this is arranged at the left of the type segments. Of course any suitable words 45 may be arranged in type upon this wheel. This name wheel is mounted on a removable block 331 (Fig. 13) and has mounted upon its hub a spur gear 332 (Figs. 13 and 14). The removable block 331 has two slots 333 50 cut in it for mounting it upon a pair of studs 334 (Fig. 3) fixed to the left-hand sub-frame 110. This plate 331 also carries a downwardly projecting portion 335 having a circular cut 336 in its lower end to 55 straddle a shaft 337 (Fig. 14). This shaft carries on its inner end a quadrant 338 which gears with spur gear 332. The shaft 337 is mounted in bosses in the sub-frame 110 and in the left-hand outer main frame. Just 60 inside of the main frame is a cam 339. Referring now to Fig. 10, pivoted on the side frame is an arm 340 carrying a roller 341 and terminating in a portion having a slot 342. The set-up plate for the name hammer 65 is situated next the side frame on the left-

hand side and consists of the plate 343 (Fig. 10) having an upper portion 344 which carries a pin 345. This pin is in the slot of the tilting plate of the name hammer in the same manner as the pins of the front set-up 70 plates 276 are in the slot 274 of the tilting plates 272. It also has a rectangular projecting portion 346 which carries a pin 347 which passes from an opening in the side frame into the slot 342 of the arm 340. At 75 the upper end of the shaft 337 is mounted a toothed segment 348 (Fig. 7). This segment has a tooth or indentation for each name on the name wheel. Attached to the bosses 349 on the main frame is an impositive 80 spring lock 350 which co-acts with the teeth of the segment 348. Also mounted upon shaft 337 is a depending arm 351 to which is attached a connecting link 352, attached at its other end to a boss on sliding carriage 353. This carriage is mounted and 85 slideable upon a rod 354 fixed in bosses 355 of one of the casings forming a part of the keyboard section of the machine. This sliding carriage 353 carries attached to its upper side a handle 356 which is provided with a pointer 357 (Fig. 2). The sliding carriage 353 carries the pin 358 adapted to co-act with a stop pawl 359 having an upwardly 90 projecting handle 360. This pawl is normally held in operative position by a spring 361. Arm 351 carries a pin 362 which acts in a slot 363 in an arm 364 pivoted at 365 on the left-hand side frame. This arm or lever 364 carries at its lower end a roller 100 366 controlled by cam 367 on cam shaft 95.

The action of these parts is as follows: In its normal position the arm 360 is tilted slightly forward with the front part of its pawl portion 359 in or out of engagement 105 with pin 358 and sliding carriage 353 is then at its rearmost position. In this position the roller 341 on arm 340 is in its deepest depression (Fig. 10) and the hammer trip of the name wheel is in its downward position and the name wheel stands blank. If 110 it is desired to print any one of the series of names opposite to an amount which is to be printed the operator takes hold of the handle 356 and pulls it forward until pointer 115 357 is opposite the word it is desired to print. The impositive lock 350 centers the total segment 348 sufficiently so that it occupies a predetermined position and the gear segment 338 turns gear 332 to which is af- 120 fixed the name type wheel turning the name wheel to a position corresponding with the name opposite the pointer 357. The succeeding operation of the machine causes cam 367 to act on roller 366 and lever 364. 125 This cam is so proportioned that it will not turn lever 364 sufficiently far to throw the name type wheel back to blank but takes it back until it stands at ditto. At this point the pin 358 abuts against the forward por- 130

tion of pawl 359 which acts as a stop and the carriage and the other parts are held in the position shown in Fig. 7. As long as handle 256 is not operated the machine 5 will continue to print ditto for any further operation of the name wheel. If the operator then desires to return the parts to zero he takes hold of handles 356 and 360 between his thumb and finger and presses 10 them together. This will cause pawl 259 to rock slightly forward releasing pin 358 when the pressure will cause the carriage to move slightly backward to its rearmost position. This movement returns the main 15 type wheel to blank. When the name plate mechanism is standing at ditto and it is desired to print a total on the total adding wheels, it is necessary to provide means to permit the toe of the name hammer, if a 20 total has been taken and when the parts are on their forward movement, to pass the name hammer trip. For this purpose I arrange the name hammer trip somewhat differently from the other trips, as shown in 25 Fig. 41. As there shown the tilting plate 445 carries a trip sliding plate 446 upon which is mounted the trip proper 447 pivoted upon stud or pin 448 of sliding plate 446 and provided with a spring 449. Upon 30 448 is one passing through the slot 450 of the tilting plate. On pushing the carriage backward to take a total trip 447 trips the name hammer but no impression is made as the hammer is then beyond the inking 35 ribbon. If the total is taken the parts are pulled forward and the toe connected with the name hammer strikes on the inclined surface of pawl 447 and forces pawl 447 downward against spring 449 out of its way. 40 This is also true where a ditto is reprinted.

The counter and its mechanism.—These are specially illustrated in Figs. 1, 2, 4, 25 and 28. It has been found desirable in practice in adding the amounts of checks 45 or any other series of papers involving numbers to be added that a record should be automatically kept by the machine of the number of operations or manipulations. For example, when the operator has added 50 up the amounts taken from fifty checks say, the machine should have an indicator which should stand at 50. At the right hand upper portion of the keyboard are shown the dials 368 of such a counter. This counter 55 is shown in details in Figs. 25, 26 and 27. This mechanism consists of a shaft 369 having a knurled wheel 370 outside of the casing of the machine. Mounted on this shaft are three wheels, 371, 372 and 373. The 60 wheel 373 carries a ratchet 374 and alongside of it a ten toothed gear wheel 375. The second wheel 372 carries a ten toothed gear 376 and wheel 371 a ten toothed gear 377. Immediately in the rear of shaft 369 is a

stationary shaft 378 which is mounted in 65 the side plates 379, 380 which form the frame of the counter. Mounted upon shaft 378 is a sleeve 381, which carries a ten toothed gear 382 and a one toothed gear 383; mounted and in mesh with gear 376 70 is a similar sleeve 384 which has a one toothed portion 385. Mounted upon shaft 378 is a pawl carrying plate 386 having a spring pressed pawl 387 mounted upon it and which co-acts with the ratchet wheel 75 374. This pawl carrying plate has a depending portion 388 which is acted upon by each operation of the driving mechanism by a pin 389 (Fig. 4) mounted on plate 17. The forward motion of the driving mechanism causes pin 389 to strike pin 388 to communicate with the next lower tooth of ratchet wheel 374 and thus feed that ratchet wheel one step forward. After wheel 374 has been turned its full complement and at 80 the time when it goes from 9 to zero the one toothed portion of sleeve 381, which has meanwhile been turning step by step, acts upon gear 376 of wheel 372 moving it forward one step. When these two wheels have 85 reached 99 the one toothed portion 385 of sleeve 384 acts upon gear 377 of wheel 371 moving it one step forward. Each one of the wheels carries recessed within it a pawl 390 (Fig. 28) each pawl is normally pressed 90 toward shaft 369 by spring 391. Shaft 369 has a slot at 392. It will be seen that each operation of the machine will cause the numeral wheels to add one so that the counter will always show the number of 100 operations or additions that have been made, providing that the counter is set at zero at the same time that the main machine is reset. The counter may be set at zero by taking hold of knurled wheel 370 and revolving it in a direction such that the tooth or slot 393 on shaft 369 will pick up the pawls 390 of the numeral wheel in whatever position they may chance to be. In this way the wheels may be moved back 110 to zero. Immediately in the rear of the counter and on the outside of the casing is a knurled wheel 393 which controls an eccentric 394 (Fig. 4) mounted on the shaft 395 of the knurled wheel. The eccentric 115 being turned throws the lower portion 388 sufficiently far forward so that the pin 389 will miss it. In this way by turning knurled wheel 393 the counting apparatus may be thrown out of operation whenever it 120 is found desirable not to use it.

The printing paper.—This is illustrated specially in Figs. 31, 32 and 34. Any suitable recording strip may be employed. This may be in the form of a single strip of 125 paper or in the form of a roll as shown in Figs. 31 and 32. I prefer, however, to use paper which is capable of manifolding or

printing in duplicate or triplicate. While it is, of course, possible to use carbons in connection with two or more strips of paper it has been found desirable to use what is 5 known as duplex paper. This is shown in Fig. 34 and consists of a highly calendered paper 396 which has upon the back of it at 397 a carbon surface sufficient to give one clean copy. Next to this is a paper 398 10 more or less absorbent in character but hard enough to give a clean copy. These two papers may be used together either in separate rolls or secured together in any manner, as by folding. When it is intended to 15 use this duplex paper or any system of mani-folding the handles 264 of the carriage should be put in their uppermost notch 265 bringing the springs 260 under greater tension and thereby increasing the force of the 20 blow of the hammers in order to give a clear manifold impression. It will be noted that the force of the blow of the hammers might also be regulated by varying the height to which the trips are raised. This is taken 25 advantage of in the printing done by the name plate. It has been found in practice that the ditto marks being so small and sharp are apt under the force of the normal printing blow used in the machine to perforate 30 the paper. In Fig. 10 it will be noticed that the cam 339 has a small depression 399 in which the roller 341 of arm 340 rests when the name wheel is in the ditto position. This position is shown in Figs. 7 and 35 10. In this position the trip of the name plate is raised sufficiently to trip the name wheel hammer but is not raised as high as the other trips are normally raised or as high as the trip of the name hammer is 40 raised for printing the other names on the name wheel. The result is that the hammer does not give as powerful a blow when the ditto marks are printed.

Rear ink ribbon.—This is specially illustrated in Figs. 2, 3, and 5. Referring to Fig. 3 it will be noticed that at the rear are the rear ink ribbon rolls 400. These rolls are mounted in the casings 401, which casings form bridges between the sub-frames 50 and the outside main frames. These rolls are preferably arranged so that the line of feed of the ink ribbon will be at an angle to the line of the type. The rolls can be removed from their supports by taking off 55 the knurled thumb piece 402 and the ribbon can be fed by means of the knurled thumb piece 403 on the outside of the rear of the machine. 404 are idle rollers over which the ink ribbon passes which carry the ribbon up above the type and in close relation to the steel plate 405 (Fig. 2) which is let into the top plate of the machine and which carries the opening 406 through which the hammers act upon the paper and rear ink

ribbon against the type of the total adding 65 wheels.

Front ink ribbon feed.—This is specially illustrated in Figs. 3, 5, 6, 14, 23 and 24. The front ink ribbon extends across and over the individual type segments and the 70 name wheel in about the same relation that the rear ink ribbon occupies with the total type wheels. 407 are the two rollers upon which this ink ribbon is wound. One roll is mounted in a casing 408 which forms a 75 bridge between the upper left-hand frame and the inner left-hand sub-frame 110. The other roll is mounted in a casting 409 which bridges between the inner right-hand sub-frame 111 and the outer right-hand main 80 frame. Referring to Fig. 23 it will be seen that upon the casing 408 are mounted three guide rolls, 410, 411 and 412. The type ribbon 413 passes from roll 407 over roll 410, under 411, over 412, then over the type 85 segments and around similar rolls 412, 411 and 410 on the other side of the machine to the other roll 407. Upon the shaft 414 upon which the left-hand roll 407 is mounted there is secured a ratchet wheel 415 by 90 means of which the ribbon is fed in one direction. There is a similar ratchet wheel 415 mounted upon the shaft 414 of the other roll. Mounted upon a stud 416 is a stop pawl 417 which at times engages with 95 ratchet wheel 415. This pawl carries a counter-balance portion 418 which co-acts with a pin 419 mounted upon a pawl carrying plate 420. The inner upper portion of this plate carries a pawl 421 which pawl acts 100 to feed the ratchet wheel when in operative position. It will be understood that these parts are duplicate on each half of the inking ribbon feeding mechanism. The lower end of pawl carrying plate 420 is attached 105 to a rock arm 422 (Fig. 5) which serves to actuate it. Rock arm 422 is mounted upon a rock shaft 423. This shaft carries in the center of the machine an arm 424 (Fig. 6) carrying a cam roller 425 bearing upon cam 110 426 on cam shaft 95. Referring to Fig. 14 it will be seen that shaft 423 carries an actuating arm 422 at each end, one for each portion of the inking ribbon feed mechanism. Mounted upon a depending portion 115 at the forward part of each of the plates 408 and 409 is a lever 427 which carries at its upper end two laterally extending pins 428 between which the ink ribbon passes. The lower parts of these levers 427 are connected by a rod 429. Secured to both parts of plate 420 is a connecting rod 430, which as shown is bent downward in order that it may pass freely between the operative parts of the machine. This rod 430 has an 120 enlarged portion 431 which has a rectangular opening 432. Attached to stud 433 upon which the right-hand portion of lever 427

is loosely secured, is also mounted a depending lever 434 which carries a loosely mounted roll 435 and on its lower end a roll 436. A pin 451 on lever 427 enters a hole in lever 434. Preferably the pin fits loosely in the hole. Motion is thus communicated from 5 427 to 434. This roll 436 extends through the opening 432 of connecting link 430. The ink ribbon carries near each end secured to it a rivet or button 437 shown at 10 the left end of Fig. 23. This button is so large that it is incapable of being drawn through the space between the two pins 428. The loosely mounted roll 435 co-acts with 15 one or the other of two notches 438 in an impositive lock spring 439 mounted upon the frame work of the machine. The operation of the various parts is as follows: Referring particularly to Fig. 23, as there 20 shown pawl 421 of the right-hand unit is in operative position with its ratchet wheel 415 and stop pawl 416 is also in engagement with the ratchet wheel. In this position of the parts the loosely mounted roller 435 occupies the right-hand notch 438 of spring 25 439 and the roll 436 is in the right-hand corner of the rectangular opening 432. In this position of the parts the ink ribbon is being fed toward the right as viewed in 30 Fig. 23. The pressure of roll 436 in the right-hand corner of the opening 432 is sufficient to keep feed pawl 421 in operative connection with its ratchet wheel and at the same time to hold the left-hand pawl 35 421 out of engagement with its ratchet wheel. Pin 419 of the left-hand unit is pressing against the counterweight 418 of left-hand locking pawl 417 and has revolved it sufficiently to throw it out of engagement 40 with its ratchet wheel. When through the oscillations of shaft 423 the pawl carrying plate 420 has been vibrated a sufficient number of times to feed the ink ribbon to the right sufficiently far, button 437 will strike 45 against pins 428 and being unable to pass through between them it will push the pins to the right and revolve levers 427 about their center. This pressure continues until it is sufficient to cause the loosely mounted 50 roll 435 to move slightly upon the projecting portion of the right-hand notch 438. During this movement roll 436 has moved freely in slot 432. This slot is made rectangular in order to allow for the vertical 55 vibration of the connecting link 420 and the sidewise movement of roll 436 at once. When lever 427 has moved sufficiently to the left, the roll 435 snaps suddenly out from the right-hand notch into the left-hand notch. This operation takes place 60 very suddenly owing to the fact that the roll 435 is loosely mounted. This causes roll 436 to suddenly strike the left-hand end of opening 432 a sharp blow sufficiently 65 strong to give a sudden tip toward the left

of the pawl carrying plates 420 and to throw the left-hand pawl 421 and stop pawl 417 into engagement with their ratchet wheel and to free the corresponding parts on the other side of the feeding mechanism. The continued oscillation of shaft 70 423 will then cause the ribbon to move in a reverse direction.

Certain parts of the main driving mechanism of the machine shown herein connected with the reciprocating handle and the main driving handle and their connections are not my invention but are the invention of one Harry T. Goss; similarly 75 also the devices shown herein for resetting the adding wheels at zero are not my invention but are the invention of one Frank Rath.

Certain parts of my improved devices 80 shown in the machine herein which are particularly applicable to the adding part of the mechanism are not claimed in this application as they form the subject-matter of another application of mine executed simultaneously herewith and to be filed simultaneously herewith.

Many modifications from and changes in the form of apparatus shown in the drawings may of course be made without departing from my invention, the essentials of 95 which are set forth in the claims appended hereto.

What I claim as new and desire to secure by Letters Patent is,—

1. The combination of a numeral bearing 100 device, means for moving such device to bring upon a specified line its different numeral characters, such means composed of a part adapted to rotate in one direction only and a rocking part adapted to be rocked one 105 way by the other part, a series of keys of different values each provided with a stop adapted when its key is operated to be thrown into the path of said rocking part to limit its movement and disengage the 110 said rocking part from the continuously rotating part, and means for returning the rocking part to its original position.

2. The combination of a numeral bearing 115 device, means for moving such device to bring upon a specified line its different numeral characters, such means composed of a part adapted to rotate in one direction only and a rocking part adapted to be rocked one way by the other part, a series of keys of different values each provided with a stop 120 adapted when its key is operated to be thrown into the path of said rocking part to limit its movement and disengage the said rocking part from the continuously rotating part, and a locking device to hold the rocking part in the position to which it has been brought.

3. The combination of a numeral bearing 125 device, means for moving such device to

bring upon a specified line its different numeral characters, such means composed of a part adapted to rotate in one direction only and a rocking part adapted to be rocked one way by the other part, a series of keys of different values each provided with a stop adapted when its key is operated to be thrown into the path of said rocking part to limit its movement and disengage the said rocking part from the continuously rotating part, a locking device to hold the rocking part in the position to which it has been brought, means for unlocking the locking device, and means for returning the rocking part to its original position.

4. The combination of a series of keys, each controlling a stop, a numeral bearing device, a shaft adapted to rotate in one direction only, a part fast on said shaft, a part loose thereon connected with the numeral bearing device, a locking piece adapted normally to lock the fast and loose parts together but when struck by any of the key stops, to free the loose part from the fast part, and a lock for holding the loose part in the position to which it has been moved.

5. The combination of a series of keys, each controlling a stop, a numeral bearing device, a shaft adapted to rotate in one direction only, a part fast on said shaft, a part loose thereon connected with the numeral bearing device, a locking piece having a projection lying normally in the path of movement of the fast part, so that the movement of the latter part is transmitted to the loose part, but moved out of said path when the locking piece is struck by any of the key stops, and a lock for holding the loose part in the position to which it has been moved, means for unlocking said lock, and means for returning the loose part to its original position.

6. The combination of a series of keys, each controlling a stop, a numeral bearing device, a shaft adapted to rotate in one direction only, a part fast on said shaft, a part loose thereon connected with the numeral bearing device, a locking piece adapted normally to lock the fast and loose parts together but when struck by any of the key stops to free the loose part from the fast part, and a lock for holding the loose part in the position to which it has been moved, means for unlocking said lock and means for positively returning the loose part to its original position.

7. The combination with mechanism for bringing characters upon a line of a signal having a clear or zero indication and a not-clear or operated indication, and means for moving from the clear to the not-clear indication actuated by the first movement of the said character-moving mechanism from the zero position.

8. The combination in a machine for

bringing characters upon a line of a signal having a clear or zero indication and a not-clear or operated indication, and means connected with and operated by the cents printing mechanism for moving from the clear to the not-clear indication.

9. The combination with mechanism for bringing characters upon a line of a signal having a clear or zero indication and a not-clear or operated indication, and means for moving from the clear to the not-clear indication actuated by the first movement of the said character-moving mechanism from the zero position, and means connected with the resetting mechanism for returning the signal to the clear position on the resetting of the said character-moving mechanism at zero.

10. In a machine for bringing characters upon a printing or adding line the combination of printing hammers a movable carriage containing the printing hammers, a spring-pressed hinged cover therefor, and a detachable catch for holding the cover in closed position.

11. In a machine for bringing characters upon a printing or adding line a movable carriage containing the paper rolls and paper feeding devices a spring-pressed hinged cover therefor, and a detachable catch for holding the cover in closed position, and a manually operated device adapted when moved one way to separate the paper rolls and when moved the other way to unlock the carriage cover.

12. In a machine for bringing characters upon two different printing lines, printing mechanism, a movable carriage containing the paper feeding devices, normally opposite one of the printing lines but adapted to be moved opposite the other printing line, means for effecting the printing upon the latter printing line when the carriage is moved opposite to it, and means actuated by the movement of the carriage to and from such printing line to feed the paper both before and after such printing to leave a space on the record strip both above and below the matter thus printed.

13. In a machine for bringing characters upon a printing line and an adding line, printing mechanism, a movable carriage containing the paper feeding devices normally opposite the printing line but adapted to be moved opposite the adding line, means for effecting the printing upon the adding line when the carriage is moved opposite to it, and means actuated by the movement of the carriage to and from such adding line to feed the paper both before and after such printing to leave a space on the record strip both above and below the total thus printed.

14. The combination of a bank of keys consisting of a number of series, a hammer

device for each series of keys, a trip for each hammer, a support for each trip along which it is adapted to move, adapted normally to hold its trip out of operative alinement with its hammer device, operating means for moving the trips along their supports at each operation of the machine, selecting means under the control of the keys, one for each series, adapted when a key of a series is operated to cause the corresponding support to bring its trip into operative alinement with its hammer device.

15. The combination of a series of keys, a hammer device therefor, a sliding trip for the hammer, a support for the trip upon which it is adapted to slide adapted normally to hold its trip out of operative alinement with the hammer device, operating means for sliding the trip along its support at each operation of the machine, selecting means under the control of the keys adapted, when a key is operated, to cause its support to bring the trip into operative alinement with the hammer device.

25. 16. The combination of a bank of keys consisting of a number of series, a hammer device for each series of keys, a sliding trip for each hammer, a support for each trip upon which the trip is adapted to slide, the support adapted normally to hold its trip out of operative alinement with the hammer device, operating means for sliding the trips at each operation of the machine along their supports, selecting means under the control of the keys, one for each series, adapted when a key of a series is operated to cause its support to bring its trip into operative alinement with its hammer device, whereby in the movement of the trips caused by the operating means only those trips will operate their hammer devices that have been brought by their supports into operative alinement.

17. The combination of a type-bearing device adapted to print words or characters, means for moving it to bring any desired type upon the printing line, and a stop adapted to be thrown into operative position upon the operation of the moving means to hold the type-bearing device upon its return at a predetermined position, whereby the character or word represented by that position will be printed at each printing operation until the next movement of the moving means.

18. The combination of a type-bearing device adapted to print words or characters, and a stop to hold the type-bearing device upon its return at a predetermined position, whereby the character or word represented by that position will be printed at each printing operation until the next movement of the moving means.

19. The combination of a type-bearing device adapted to print words or characters,

means for moving it to bring any desired type upon the printing line, and a stop normally held out of operative position but adapted to be thrown into operative position upon the operation of the moving means to hold the type-bearing device upon its return at a predetermined position, whereby the character or word represented by that position will be printed at each printing operation until the next movement of the moving means, and means for moving the stop into its inoperative position.

20. The combination of a type-bearing device adapted to print words and ditto marks, means for moving it to bring any desired type upon the printing line, and a stop normally held out of operative position but adapted to be thrown into operative position upon the operation of the moving means to hold the type-bearing device upon its return at the ditto position, whereby the ditto marks will be printed at each printing operation until the next movement of the moving means.

21. The combination of a type-bearing device adapted to print words or characters, means for moving it to bring any desired type upon the printing line, and a stop adapted to be thrown into operative position upon the operation of the moving means to hold the type-bearing device upon its return at a predetermined position, whereby the character or word represented by that position will be printed at each printing operation until the next movement of the moving means, and printing devices for printing the word or character standing on the printing line adapted to deliver a lighter blow when the type-bearing device stands at the said predetermined position.

22. The combination of a type-bearing device adapted to print words and ditto marks, means for moving it to bring any desired type upon the printing line, and a stop normally held out of operative position but adapted to be thrown into operative position upon the operation of the moving means to hold the type-bearing device upon its return at the ditto position, whereby the ditto marks will be printed at each printing operation until the next movement of the moving means and printing devices for printing the word or character standing on the printing line adapted to deliver a lighter blow when the ditto marks are on the printing line.

23. The combination of a type-bearing device adapted to print words or characters, means for moving it to bring any desired type upon the printing line, and printing devices for printing the word or character standing on the printing line adapted to deliver a lighter blow when the type-bearing device stands at one position than when it stands at another.

24. The combination of a type-bearing de-

- vice adapted to print words and ditto marks, a printing hammer for printing the word or ditto marks when on the printing line, a trip for operating the hammer, means for causing the trip to operate the hammer, and a device for varying the extent of engagement of the trip and hammer to cause a lighter blow to be given when the ditto marks are to be printed.
- 10 25. The combination of a type-bearing device adapted to print suitable characters, a printing hammer therefor, a trip for operating the hammer, and means for adjusting the extent of engagement of the trip and hammer to vary the pressure of the blow to be given.
- 20 26. The combination of a type-bearing member, means for normally holding said member with its zero slightly off the printing line and for moving said member first to bring the zero upon the printing line and then the reverse way to bring any of the type upon said member upon the line.
- 25 27. The combination of a type-bearing member, means for normally holding said member with its zero slightly off the printing line, and for moving said member first to bring the zero upon the printing line and then the reverse way to bring any of the type upon said member upon the line, and a pawl for the type-bearing member normally held

out of operative engagement until the zero arrives on the printing line and then moved into operative engagement and kept in such engagement until after the printing operation.

28. The combination of a type-bearing segment, operating means adapted normally to hold the zero slightly in advance of the printing line and to move the segment backward to bring the zero upon said line and then forward to bring any of the type upon said line, a ratchet upon the segment, a pawl adapted to engage therewith, and means for holding the pawl out of engagement while the zero is being moved back upon the line and means for holding it in engagement during the forward movement of the segment.

29. The combination in a machine for bringing characters upon a line, of a signal having a clear or zero indication and a not clear or operated indication, and means automatically actuated for moving from the clear to the not clear indication.

In testimony whereof, I have signed my name to this specification, in the presence of two subscribing witnesses.

GEORGE L. MARTIN.
